UNITED STATES PATENT OFFICE

118,962

DESIGN FOR A COMPUTING AND LISTING MACHINE

Louis M. Llorens, New Haven, Conn., assignor to
Swift Business Machines Corporation, New
York, N. Y., a corporation of Delaware

Application October 30, 1939, Serial No. 87,941

Term of patent 14 years

To all whom it may concern:

Be it known that I, Louis M. Llorens, a citizen of the United States, residing in New Haven, in the county of New Haven and State of Connecticut, have invented a new, original, and ornamental Design for a Computing and Listing Machine, of which the following is a specification, reference being had to the accompanying drawings forming a part thereof, wherein:

Fig. 1 is a perspective plan view showing the top and two sides of a computing and listing ma-

chine as viewed from one of the front corners of the machine; and

Fig. 2 is a perspective view showing the back and one side, and part of the top of a computing and listing machine as viewed from one of the rear corners.

I claim:

The ornamental design for a computing and listing machine, substantially as shown.

LOUIS M. LLORENS.
